UNITED STATES PATENT OFFICE.

GEORGE C. HICKS, JR., OF CONNERSVILLE, INDIANA.

GAS-ENGINE STARTER.

No. 841,149.

Specification of Letters Patent.

Patented Jan. 15, 1907.

Application filed November 22, 1905. Serial No. 288,515.

To all whom it may concern:

Be it known that I, GEORGE C. HICKS, Jr., a citizen of the United States, residing at Connersville, Fayette county, Indiana, (post-office address, Connersville, Indiana,) have invented certain new and useful Improvements in Gas-Engine Starters, of which the following is a specification.

This invention pertains to improvements in that class of devices designed to facilitate the starting of gas-engines.

While the invention is not limited to any specific adaptation, it has been developed with special reference to employment upon automobiles, and it is in connection with such an adaptation that I have chosen to illustrate an exemplification of the invention.

The invention will be readily understood from the following description, taken in connection with the accompanying drawings, in which—

Figure 1 is a side elevation of an automobile of gas-engine type fitted with my improved starter; Fig. 2, a side elevation of the starter; Fig. 3, a front elevation, part vertical section, of the same; Fig. 4, a side elevation, part vertical section, of portions of the device; Fig. 5, a front elevation of a portion of the main lever, and Fig. 6 a side elevation of the main pawl.

In the drawings, 1 indicates as a whole an automobile of gas-engine type; 2, its gas-engine; 3, its engine-shaft; 4, a frame part fixed relative to the engine; 5, a bearing secured to the frame part with its axis parallel to that of the engine-shaft; 6, a rotator or spindle journaled therein; 7, a sprocket-wheel fast on the spindle; 8, a sprocket-wheel loose on the engine-shaft; 9, a chain connecting the two sprocket-wheels; 10, a ratchet fast with sprocket-wheel 8 and engaged by a pawl carried by some part turning with the engine-shaft—as, for instance, the fly-wheel; 11, a notched wheel fast on the spindle; 12, a hand-lever having its heel loosely pivoted upon the spindle, the heel of the lever being shown as bifurcated to straddle the notched wheel; 13, a pawl pivoted to the hand-lever and having a tooth adapted to engage the notches of the notched wheel and form a clutching device for temporarily locking the hand-lever to the spindle; 14, a pawl-lifting grip-lever pivoted on the hand-lever near its handle; 15, a rod connecting the grip-lever with the pawl; 16, a spring on this rod tending to urge and hold the pawl into engagement

with the notched wheel; 17, a ratchet-wheel fast on the spindle; 18, a stop-pawl pivoted on the frame part and co-operating with the ratchet-wheel; 19, an arm fast with the stop-pawl; 20, a lug projecting from the heel of the hand-lever and adapted when the hand-lever is given certain movement to engage on 19 and tip the stop-pawl out of engagement with the ratchet-wheel; 21, a disk fast on the spindle; 22, a spiral spring having one end secured to the disk and its other end secured to the fixed bearing of the spindle; 23, 24, and 25, lines indicating certain angular positions for the hand-lever, and 26 a spring for urging and holding the stop-pawl into engagement with the ratchet-wheel.

In Fig. 1 the engine motion is in clockwise direction, as indicated by the arrow, and it is the duty of the starting device to start the engine in such direction. Spring 22 is so arranged as when under tension to tend to turn the spindle in clockwise direction, and the stop-pawl and its ratchet-wheel are so constructed as to prevent the turning of the spindle in clockwise direction, while permitting it to be freely turned in the opposite direction. The hand-lever, with its pawl co-operating with the notched wheel, may turn the spindle in either direction to hold it, but in practice is employed only in turning the spindle upon the clock and in holding it. When the spring is energized and permitted to turn the spindle in clockwise direction, then the chain will in an obvious manner impart starting motion to the engine. The illustrated system of transmission between the spindle and the engine-shaft is merely typical. In an automobile the hand-lever should be so mounted that it may be conveniently actuated by the driver from his position on the seat, and the connection between the spindle and the engine would manifestly vary with the exigencies of automobile construction. In view of the preceding remarks the engine itself may be generally ignored in future description, and the device may be looked upon as one for endowing the spindle with a controlled starting capacity in proper direction.

Assume everything at rest and the spring unstrained and the parts in the position indicated in the drawings. The hand-lever being grasped and the grip-lever pressed, the tooth of the pawl is disengaged from the notched wheel, whereupon the hand-lever may be moved idly forward—say to the po-

sition indicated by line 24. The tooth of the pawl is then permitted to engage the notched wheel, and thereupon the hand-lever is to be drawn back—say to near the position indicated by the line 23. The effect of this back stroke has been to turn the spindle through a certain angular distance and put the spring under a certain degree of tension. The stop-pawl holds the spindle in its new angular position. One or more additional strokes may, if necessary, be given to the hand-lever to increase the tension upon the spring. The result is that this spindle is energized, with a capacity to turn in clockwise direction, but is restrained against such turning by the action of the stop-pawl. The device may be left in this condition, if desired, and its stored energy utilized in the future when occasion requires, or its energy may, if desired, be instantly put into action.

When the energy of the starter is to be utilized, then the hand-lever, with the tooth of its pawl still in engagement with the notched wheel, is drawn backward an extra distance, beyond the position indicated by line 23 and, say, to the position indicated by line 25. The effect of this excess motion is to cause lug 20 to release the stop-pawl from the ratchet-wheel. So far as the stop-pawl is concerned, the spindle would now be at liberty to yield to the spring and make its starting rotation; but the spindle is still restrained against rotation by being held by the hand-lever. Upon actuating the grip-lever the tooth of the pawl is released from the notched wheel, and thereupon the spring gives to the spindle the desired motion of rotation. The energy of the spring thus remains stored for use as desired and under complete control of the hand-lever, for when the stop-pawl has been released the spring is still restrained, and if for any reason there be a change of purpose the hand-lever may be advanced and the stop-pawl again permitted to go into action. If by carelessness the hand-lever should be released after it has released the stop-pawl and while its own pawl is still engaging the notched wheel, still the hand-lever will not be flung forward by the spring, for the reason that early in its advancing motion it would permit the stop-pawl to again go on guard. In short, the spring is at liberty to exercise its energy only while the hand-lever holds the stop-pawl released and while the hand-lever is itself held in position corresponding with such release of the stop-pawl. After the starter has done its work and the engine is in motion the engine-shaft carries the pawl around its ratchet idly, thus permitting no motion to the starting mechanism. In the present case the ratchet-wheel is loose on the engine-shaft and positively connected with the starting device, while the pawl that co-operates with this ratchet-wheel is fast with the engine-

shaft. The result is that centrifugal force tends to throw the pawl outwardly away from the ratchet-wheel, and thus entirely prevent or considerably lessen the noise and wear of the pawl.

It is to be understood that the definition of my invention is to be gathered from the claims, in which my invention is particularly pointed out, the described construction being merely a single exemplification representing the best form in which I at present contemplate applying my invention.

I claim—

1. The combination, substantially as set forth, of a shaft to be rotated by power in a given direction, a ratchet-wheel loose on said shaft, a pawl carried by the shaft and co-operating with the ratchet-wheel in such manner that the ratchet-wheel may act as a driver and turn the shaft in normal advance direction, and mechanism independent of said shaft for turning said ratchet-wheel in advance direction; said pawl being so mounted that when said shaft assumes its normal rotative speed the pawl is urged away from the ratchet by centrifugal force.

2. The combination, substantially as set forth, of a rotator to be angularly advanced, a spring connected therewith and tending when released under strain to advance the rotator, a locking device to hold the rotator in retreated position against the urgency of the spring, an angularly-movable handle, a retractable connection between the handle and the rotator serving to turn it in retreating direction and put the spring under strain, and releasing mechanism connected with said handle and locking device whereby an excess retreating movement of the handle releases the locking device.

3. The combination, substantially as set forth, of a rotator to be angularly advanced, a spring connected therewith and tending when released under strain to advance the rotator, a ratchet-wheel carried by the rotator, a stop-pawl engaging the ratchet-wheel and serving to hold the rotator in retreated position against the urgency of the spring, an angularly-movable handle, a retractable connection between the handle and the rotator serving to turn it in retreating direction and put the spring under strain, and releasing mechanism connected with said handle and stop-pawl whereby an excess retreating movement of the handle releases the ratchet-wheel.

4. The combination, substantially as set forth, of a rotator to be angularly advanced, a spring connected therewith and tending when released under strain to advance the rotator, a ratchet-wheel carried by the rotator, a stop-pawl engaging the ratchet-wheel and serving to hold it in retreated position against the urgency of the spring, an angularly-movable handle, a retractable connec-

tion between the handle and the rotator serving to turn it in retreating direction and put the spring under strain, and a part carried by said handle and adapted to engage the stop-pawl and release it from the ratchet-wheel when the handle is given an excess retreating movement.

5. The combination, substantially as set forth, of a rotator to be angularly advanced, a spring connected therewith and tending when released under strain to advance the rotator, a locking device to hold the rotator in retreated position against the urgency of the spring, a handle mounted for angular

10 movement on the axis of the rotator and free of the rotator, hand-operated clutch mechanism carried by the handle and serving to temporarily lock the handle to the rotator whereby the handle may be employed in turning and temporarily holding the rotator, and releasing mechanism connected with said handle and locking device whereby an excess retreating movement of the handle releases the locking device.

15 6. The combination, substantially as set forth, of a rotator to be angularly advanced, a spring connected therewith and tending when released under strain to advance the rotator, a locking device to hold the rotator

20 in retreated position against the urgency of the spring, a notched wheel fast with the rotator, an angularly-movable handle loosely pivoted on the rotator, a pawl carried by the

25 handle and coöperating with the notched wheel, a spring urging the pawl normally into engagement with the notched wheel, a pawl-releasing device carried by the handle for releasing the pawl from the notched wheel, and releasing mechanism connected with said handle and locking device whereby an excess retreating movement of the handle releases the locking device.

30 7. The combination, substantially as set forth, of a rotator to be angularly advanced, a spring connected therewith and tending when released under strain to advance the rotator, a ratchet-wheel carried by the rotator, a stop-pawl coöperating with the ratchet-wheel to hold the rotator in retreated

35 position against the urgency of the spring, a hand-lever loosely pivoted upon the rotator, a notched wheel fast with the rotator, a projection carried by the handle to engage and release the stop-pawl when the handle is given an excess retreating movement, a pawl 55 carried by the handle and coöperating with the notched wheel, a spring normally urging the pawl into engagement with the notched wheel, and a grip-lever carried by the hand-lever and connected to its pawl to serve in 60 disengaging the pawl from the notched wheel.

8. The combination, substantially as set forth, of a bearing, a spindle journaled therein, a disk fast on the spindle, a spiral spring 65 having one end secured to the disk and having its other end fixed, a ratchet-wheel fast on the spindle, a stop-pawl coöperating with the ratchet-wheel and serving to hold the spindle against rotation in the direction in 70 which it is urged by the spring when under tension, a notched wheel fast with the spindle, a hand-lever loosely pivoted on the spindle, a pawl carried by the hand-lever and engaging the notched wheel and serving to 75 clutch the hand-lever temporarily to the spindle, a spring urging and holding the pawl into engagement with the notched wheel, and a connection from the pawl to the handle of the lever whereby the hand grasping the 80 hand-lever may release the pawl from the notched wheel.

9. In starting mechanism, the combination of a rotator, a motor-spring therefor, a clutch element on the rotator and a fixed detent coöperating with said clutch, an operating member, a retractable connection between the operating member and the rotator for placing the spring in position to impel the rotator, and coöperating members carried by 85 the handle and detent arranged so that movement of the handle within a limited part of its angular motion serves to release and reengage the detent.
